UNITED STATES PATENT OFFICE.

ALEXANDER McCREERY, OF HIAWATHA, KANSAS.

WHEEL-PLOW.

1,212,526.

Specification of Letters Patent. Patented Jan. 16, 1917.

Original application filed May 25, 1915, Serial No. 30,404. Divided and this application filed September 22, 1915. Serial No. 51,958.

To all whom it may concern:

Be it known that I, ALEXANDER McCREERY, a citizen of the United States, residing at Hiawatha, in the county of Brown and State of Kansas, have invented certain new and useful Improvements in Wheel-Plows, of which the following is a specification.

This invention has relation to wheel plows and chiefly to the motor driven plow disclosed in an application for patent filed by me in the United States on the 25th day of May 1915, Serial No. 30,404 of which this application is a divisional part.

The invention relates to the mountings and adjusting means whereby the plows are enabled to make a short turn and may be raised or lowered to meet varying surface and soil conditions, my primary object being the provision of a motor-driven machine which may be turned around a corner without withdrawing the plows from the ground.

A further purpose of the invention is the provision of an implement which is balanced and adapted to turn with the least resistance and in the shortest space possible; thereby admitting of the implement turning a corner squarely in either direction or turning to any required degree as occasion may necessitate.

The invention further aims to provide means whereby the plows or earth treating devices may be adjusted vertically without changing the pitch or angle of the shovels or like parts so that when adjusted to any position the plows remain parallel to a given position.

With these and other objects in view, which will readily appear as the nature of the invention is better understood, the same consists in the improved construction and novel arrangement and combination of parts which will be hereinafter fully described and particularly claimed.

In the accompanying drawings has been illustrated a simple and preferred form of the invention, it being, however, understood that no limitation is necessarily made to the precise structural details therein exhibited, but that changes, alterations and modifications within the scope of the invention as claimed may be resorted to when desired.

Referring to the drawings,—Figure 1 is a top plan view of the main frame and supporting wheels showing more clearly the relation of the connecting means between the front and rear wheels for steering and illustrating the relation of the plows and adjusting means embodying the invention; Fig. 2 is a detail perspective view of the plows and the means associated therewith for effecting a raising and a lowering thereof; Fig. 3 is a detail view of the adjusting means for the plows; Fig. 4 is a detail view of part of the plow adjusting mechanism; Fig. 5 is a detail view of the rear portion of the implement showing more clearly the mountings and power transmitting mechanism for the rear wheel.

Corresponding and like parts are referred to in the following description and indicated in all the views of the drawings, by the same reference characters.

The main frame comprises a transversely disposed beam 1, which is substantially of J-form, the short member of such beam being bolted or attached in any manner to a vertically disposed bracket 2. A vertically disposed sleeve 3 is mounted in bearings at the upper and lower end of the bracket 2. A spindle 4 projects laterally from the lower end of the sleeve 3 and a bull or drive wheel 5 is mounted thereon. A vertically disposed shaft 6 is mounted in the sleeve 3. A pinion 7 is secured to the lower end of the shaft 6 and its teeth are in mesh with the teeth of a gear wheel 8 attached to a side of the drive wheel 5. The gear elements 7 and 8 are of the bevel type although it is to be understood that gearing of any form may be employed which will admit of transmitting motion from the shaft 6 to the wheel 5. The shaft 6 is adapted to be connected in any manner to the motor, not shown, which is mounted upon the machine for propelling the same. A frame 12 of substantially U-form embraces the rear portion of the wheel 5 and is provided with a clevis 13 for convenience of hitching a wagon, implement or other device to the machine to be propelled thereby with the result that the machine may be utilized as a tractor. One member of the frame 12 is connected in any manner to the sleeve 3 and the other member is in-

clined outwardly and forwardly and receives the outer end of the spindle 4. The frame 12 turns with the sleeve 3 and with the drive wheel 5, as indicated by the dotted lines in Fig. 1.

The front wheel is designated by the numeral 26 and is mounted to turn about a vertical axis and is adjustable vertically. The standard carrying the front wheel 26 is provided with a laterally extending arm 29 to which a link 35 is connected at its forward end. A link 36 is connected to the rear end of the link 35 and the rear end of said link 36 is connected to an arm of a segmental gear 42 which is in mesh with a worm 43 forming part of a shaft 44. A gear wheel 45 is secured to the shaft 44 and is adapted to mesh with a companion gear wheel 46 secured to a manually operable shaft 47 which is provided at its upper rear end with a hand wheel 48, thereby admitting of the implement being steered by hand when desired.

It is to be understood that the shaft 44 may be driven from the same motor which propels the machine as fully disclosed in my aforesaid parent application although the connections between the shaft 44 and the motor are not an essential part of the present invention. The shaft 44 is provided at its rear end with a sprocket wheel 119 which is connected by means of a sprocket chain 120 with a sprocket pinion 121 secured to a worm shaft 122 and which worm shaft is in mesh with a segmental gear wheel 123 having connection with the sleeve 3 and frame 12. The center of the gear 123 coincides with the axis of the vertical shaft 6. The axis of the spindle 4 is in line with the axis of the shaft 6. By means of the described mechanism the wheels 5 and 26 may be turned in horizontal planes to steer the machine, and in all positions of the wheels their axes will lie on lines which intersect at the point or center about which the machine turns, hence the power required to drive the machine when making a turn is not in excess of that required for propelling it in a straight course. On reference to Fig. 1 of the drawings it will be observed that the landside 124 is curved longitudinally, thereby facilitating the turning of the machine to the right.

The plow shovels are indicated at 90 and are attached to the standards of plow beams 91 and 92 which converge toward their forward ends where they are connected and provided with a clevis having a longitudinally elongated opening 93 through which passes a crank pin 94 carried by an arm 95 projecting from a shaft 96. An arm 97 projects from the shaft 96 at an angle to the arm 95. A rod 98 connects the arm 97 with an arm 76 projecting from a transversely disposed shaft 72. The shaft 72 is formed with a

70 mounted. The plow beam 91 is mounted directly upon said crank portion whereas the plow beam 92 is mounted thereon by means of a bracket which comprises members 99 and 100. The member 99 is attached to the lower rear portion of the beam 91 and extends forwardly and laterally. The member 100 is attached to the beam 92 and extends rearwardly and laterally. The opposing ends of the members 99 and 100 are bolted or otherwise secured and fitted about the crank portion 73 which is mounted 75 therein.

The crank shaft 72 upon which the plows are mounted is provided with arms 76 and 77, the arm 76 radiating from the axis of the crank shaft whereas the arm 77 projects from the crank portion 73. This crank shaft may be turned either by hand or by power. A shaft 78 paralleling the crank 85 shaft 72 is provided with an arm 79 which is connected by means of a rod 80 with the crank portion 39 of a vertically disposed crank shaft 38 to which gear 42 is secured. A lever 81 is mounted upon the shaft 78 and is provided with a latch member 88 which is adapted to coöperate with a toothed segment 83 which is secured to a part of the main frame. A rod 84 connects the lever 81 with the arm 77 and this rod has adjustable 90 connection both with the arm 77 and the lever 81 as shown in Fig. 4. The lever 81 is formed with a portion having a slot 85 which receives the connection joining the rod 84 to the lever. This connection is adjustable in slot 85 and varies the adjustment 95 of the plows according to the throw of the lever.

The adjustable connection of the rod 84 with the arm 77 permits the plows to be set 100 at normal working depth when the lever 81 is at or about the central point of its movement. Moving the lever forward from this point at once interferes with correct plowing, the purpose of such forward movement, 105 which is always accomplished manually, being strictly and solely to lift the plows entirely clear of the ground so as to clear a stone or to move the machine to another place to permit a new land. The latch 88 holds the lever either in its central or forward position. An arm 86 is loose upon the shaft 78 and is yieldably connected thereto by means of a spring 87 which is of helical form and mounted upon such shaft. One 110 end of the spring 87 is attached to the shaft 78 whereas the opposite end engages the arm 86. The arm 86 acts as a trip to disengage the latch 88 from the toothed segment 83 when the plows are automatically adjusted by power derived from the shaft 38. The shaft 38 is disposed so that its crank portion 39 is in line with the direction of movement of the machine so that no matter 115 which direction the shaft 38 is turned the 120

shaft 78 will be rotated in the same direction, thereby lowering the land wheel and the plows relative to the balance of the machine. The crank portion 39 of the shaft 38 normally extends forward, hence rotation of the shaft 38 to the right or to the left exerts a rearward push upon the rod 80, whereby the shaft 78 is turned. The arm 86 is provided with a tappet 89 which is mounted thereon so as to be projected into or out of the path of the latch 88 and is provided with an inclined upper edge adapted to ride under the lower end of the latch and thereby raise the same. The tappet 89 is preferably pivoted to the arm 86 and may be turned aside so as to clear the latch 88 as shown in Fig. 3 or may be adjusted to align with the arm 86 so as to engage the latch 88 and effect disengagement of the same from the toothed segment 82 when the plows are automatically adjusted by power derived from the shaft 28. When the shaft 78 is turned by the rearward push of the rod 80, the arm 86 slides the inclined upper end of the tappet 89 under the latch 88, thereby raising said latch out of engagement with the segment 82, and, as the rotation of the shaft continues, the high shouldered end of the tappet will engage against the latch and will force the same and the lever 81 to the extreme rear position, whereupon a second latch 82, which is pivoted to the lever, engages the last tooth or rear end of the segment and holds the lever while the tappet and the arm 86 may turn to normal position. The latch 82 is preferably constructed so as to ride rearwardly over the segment but engage the same on an attempted forward movement of the lever. The latches 82 and 88 are raised by a single handle on the lever 81 but the latch 88 may rise under the influence of the tappet without affecting the latch 82.

The land wheel 68 is mounted upon the crank portion 67 of a shaft 66. A segmental gear 63 secured to the shaft 66 is adapted to mesh with a companion gear 64 attached to the shaft 63. Turning of the shaft 63 effects a corresponding turning of the shaft 66 and a relative raising or lowering of the land wheel whereby the main frame may be adjusted vertically upon the land side. A lever 69 is fixed upon the outer end of the shaft 63 and is provided with a latch 70 to coöperate with a toothed segment 71 loose upon the shaft 63 whereby such shaft may be rotated when required to effect vertical adjustment of the landside of the machine. An arm 74 secured to the crank shaft 72 is connected by means of a rod 75 with the segment 71. It will thus be understood that rotation of the land wheel supporting shaft 66 is effected simultaneously with rotation of the plow supporting shaft 72. As the land wheel 68 is relatively lowered the plows are correspondingly lowered. It is to be

understood that the land wheel 68 may be adjusted independently of the plows which may remain at a fixed depth relative to the main frame in general plowing. Raising the plows admits of the machine clearing stones 70 and other objects and to be thrown out of action when desired.

The bracket members 99 and 100 transfer the side pressure of the plows to the main frame and wheels so that land-sides may be omitted. The machine will, therefore, run easily and a light construction of motor and propelling apparatus may be used. The several cranks and connecting parts which carry the plows are so proportioned and placed at such angles to each other that they keep the plows level and relatively lowered while the machine rises so that the plows will remain in the ground while the machine is turning a corner. The plows can be lowered automatically or by hand by means of the lever 81 and by means of said lever they can also be raised to a non-working position above the ground.

It is to be understood that the front wheel 90 runs in the open furrow against the bank and thereby automatically steers the machine when going ahead while the driving wheel 5 runs in the furrow behind the last plow and both these wheels ride up out of the furrow when turning a corner. When the corner-turning mechanism is set in motion and the drive or bull-wheel 5 rises from the furrow, the lever 81 is automatically pushed back its full swing and the latch 82 will engage the tooth at the rear end of the segment 83 to hold the lever in its rearmost position. The bull-wheel does not always rise the same distance and the slot 85 permits the pivotal connection between the lever 81 and the rod 84 to be shifted so that the plows will be lowered the same distance that the bull-wheel and frame rises. As before stated, the corner-turning mechanism imparts a rotary movement to the upright shaft 38 and the crank 39 of the same pushes the bar 80 rearwardly and thereby rocks the shaft 76. The arm 86 and tappet 89, of course, follow the movement of the shaft 76, the latch 88 being raised out of engagement with the segment 83 and being engaged by the forward upturned extremity of the tappet so that the latch and the lever will be swung rearwardly. As the steering gear turns to straight ahead position, the shaft 78 is rocked forwardly; but the lever 81 is held in its rear position so that the crank 73 will not rise and the plows will remain in their lowered position. When the straight ahead travel is resumed, the lever is swung forwardly manually and the plows thereby raised to normal plowing position. The spring 87 yields so as to prevent breakage by jamming of the parts if the pivot in the slot 85 should be improperly adjusted but, if

the adjustment is right and the operation normal, the tension of the spring will hold the parts in their operative relation.

In order to keep the plows level laterally when the bull-wheel rises from the furrow, the land wheel must be lowered to the same degree that the machine is raised. This result is attained by the connection between the shafts 72 and 63 whereby the land wheel axle or shaft 66 receives the same movement as the shaft 72.

It is to be understood that moving the lever 81 forward from the point of normal plowing position, as previously described, is for one purpose and moving the lever backward from said point (which is done by power and lowers the land wheel and plows relative to the frame) is for a distinctly separate purpose. This latter purpose is to keep the plows in the ground at the same depth while turning corners as while running straight ahead. The moment the corner-turning gearing is tripped and set in motion, the driving wheel is quickly steered to the right or to the left and immediately rolls up out of the furrow in which it normally runs onto the surface of the ground. This operation naturally would raise the main frame and plows with the driving wheel were not the plows automatically adjusted downward simultaneously with the turning and rising of the driving wheel to the surface. At this particular moment, the front end of the machine remains vertically stationary. The cranks are so proportioned and located that when the driving wheel rises to the surface and the plows are automatically adjusted, as described, the plows really remain at their original and normal working depth and position so that the actual result is that the rear portion of the machine, except the plows and the land wheel, rises. This operation permits the machine to turn a square corner with the plows as a pivot. The adjustment of the land wheel simultaneously with the plows keeps the entire machine level laterally, the bottoms of the plows being kept parallel with the surface of the ground both laterally and longitudinally. After the driving wheel and the front wheel have been steered to one side, the driving wheel rolls approximately one-fourth of a revolution in a circular path, whereupon it is quickly steered to straight-ahead position again and simultaneously with the later movement, the arm 86 and the tappet 89 are returned to normal position but the lever 81 remains locked in its rear position until the driving wheel drops into the furrow back of the plow whereupon the lever is returned by hand to the normal position.

Having thus described the invention, what is claimed as new is:

65 1. In a machine of the character de-

scribed, a main frame, front and rear wheels positively connected for simultaneous adjustment to admit of the machine making a short turn, and shovel plows mounted upon the main frame and provided with longitudinally curved landsides to admit of the machine turning with a minimum amount of resistance. 70

2. In combination, a frame, a shaft having a crank portion, a beam mounted upon the crank portion of the shaft, a second beam, a two-part bracket having corresponding ends brought together about the crank portion of the shaft and having the parts attached to the respective beams, and means 75 for turning the shaft to effect a raising or a lowering of the beams. 80

3. In combination, a crank shaft, a beam mounted upon the crank portion of the crank shaft, a second shaft paralleling the 85 crank shaft, connecting means between the two shafts to cause them to turn together, a third shaft having a crank axle upon which is mounted a supporting wheel, gearing between the second and third shafts, and an 90 operating lever connected with the second shaft. 95

4. In combination, a crank shaft, a beam mounted upon the crank portion of the crank shaft, an arm projecting from the 95 crank shaft, a second shaft, an operating lever mounted upon the second shaft to turn therewith, an adjustable connection between the operating lever and arm of the crank shaft, a latch mounted upon the operating 100 lever, a toothed segment to be engaged by the latch, a tappet for operating the latch and adapted to be thrown into or out of the path thereof, and a support for the tappet. 105

5. In combination, a crank shaft having 110 an arm projecting therefrom, a beam mounted upon the crank shaft, a second shaft having an arm projecting therefrom, an operating lever secured to the second shaft, a toothed segment, a latch mounted upon the operating lever and adapted to engage the toothed segment, a support having yieldable connection with the second shaft, a tappet mounted upon the support and adapted to be thrown into and out of the 115 path of the latch, a third shaft having a crank portion, and connecting means between the crank portion of the third shaft and the arm of the second shaft for turning the latter whether the third shaft is turned 120 to the right or to the left. 125

6. In combination, a shaft having a crank axle upon which is mounted a supporting wheel, a second shaft geared to the crank axle shaft, an operating lever provided with a latch, a toothed segment connected with the second shaft, a crank shaft having an arm connected with the toothed segment, a beam mounted upon the crank shaft, a third shaft having an arm, an operating lever con- 130

nected with the third shaft, a latch mounted upon the operating lever, a toothed segment for coöperating with the latch mounted upon the operating lever of the third shaft, a support yieldably connected with the third shaft, a tappet mounted upon the support and adapted to be thrown into or out of the path of the latch, and a fourth shaft having

a crank portion which is connected with an arm of the third shaft to turn the latter in 10 the same direction whether the fourth shaft is turned to the right or to the left so as to effect opposite vertical adjustment of the supporting wheel and beam.

In testimony whereof I affix my signature. 15

ALEXANDER McCREERY. [L. S.]
